UNITED STATES PATENT OFFICE.

WILLIAM SAKLAD, OF BOSTON, MASSACHUSETTS.

METHOD OF MAKING BOOTS AND SHOES.

Application filed October 12, 1925. Serial No. 61,952.

My present invention is a novel and improved method of making boots and shoes, preferably embodying novel, orthopedic and arch supporting features.

In my developments of the improvements in the manufacture of boots and shoes, particularly those intended for arch supporting features, I have discovered that a defect in prior boot and shoe manufacture consists in the failure of the last maker, the shoe maker, and the designer, as well as the public, in appreciating fully the structural characteristics of the human foot. I have, therefore, designed my present improved shoe construction to follow more closely than has heretofore been done, the foot outline, both in the transverse arch, as well, also as to follow the curvature in the inner portion of the foot and to provide correspondingly foot supporting structures to cooperate with these contours. To this end I have invented an improved last, shown, illustrated, described and claimed in my prior Patent No. 1,586,120 dated May 25, 1926, on which to build and construct my improved shoe. Preferably also I utilize the desirable features of my shoe and arch supporter invention, illustrated in my prior Patent No. 1,506,945, dated September 2, 1924.

Referring to the drawings illustrating a preferred embodiment of the invention, Fig. 1 is a side view of a "left" shoe, partly in cross section, illustrating my novel method of shoe making;

Fig. 2 is a cross-sectional view on the line 2—2 of Fig. 1, illustrating a welt shoe construction;

Fig. 3 is a perspective view of the wedge heel lift which I employ, as will be more fully explained; and

Fig. 4 is a fragmentary cross-sectional view corresponding to Fig. 2, but showing the invention as applied to a McKay shoe.

As shown in the drawings, the boot and shoe upper, designated generally at 1, may be of any suitable size, design, style or material, men's, women's or children's. In carrying out my improved method, I assemble the shoe upper materials on a last of the form and contour illustrated in my said Patent No. 1,586,120, apply the insole to the last, beat the same so that it will conform to the recess in the last to receive the arch support for the transverse portion of the foot, as shown and explained in my said patent, and in the improved last application, then

last the shoe, and in case of welt shoe construction, apply the welt and then the outsole. In case of McKay shoe construction, I apply the outsole directly, withdraw the last and stitch the shoe. Because of the special configuration of my improved shoe made on my novel last, the heel part of the outsole, particularly on the inside of the arch of each foot, is slightly raised, instead of being substantially horizontal or long as in normal shoe construction. Therefore the heel seat, in order to be fitted with the usual heels, is "offset" to a certain extent. To build up this offset portion and compensate for the same, I apply the wedge member shown in Fig. 3. In the case of a welt shoe construction, wherein the insole 2, and welt 3 are attached by inseam stitching 4, and the outsole 5 secured thereto by the welt stitching 6, I apply this wedge 10 substantially where the welt ends at the heel breast line 11. In the case of McKay shoe construction, wherein the insole 14 is attached directly to the outsole 15 by through and through stitching 16, the wedge 10 is also applied at the line of the heel breast, but there is no welt structure to consider. In either instance, the heel wedge 10 illustrates the extent to which my shoe and last more closely and snugly follows the outline of the inner arch portion of the shoe, aiding in supporting the foot at this point. As shown in Figs. 1 and 3, the corrective wedge member 10 is substantially rectangular in form, and has its point of greatest thickness at the inner heel breast and forward side of the heel where the wedge is exposed. The specific positioning of this wedge is of the greatest importance in the shoe illustrated in the drawings. I have, therefore, claimed the particular shape and positioning of this wedge member 10 herein. Thereupon the heel 20 of any ordinary or desired type can be applied, either a leather heel base, heel base and rubber heel, or otherwise, and to which the toplift 21 of leather or rubber is secured.

The feature of my shoe as thus described, i. e., carrying the line and curve of the sole and hence of the foot supporting edge of the sole, more closely and snugly along the longitudinal arch at the inner portion, as evidenced by the offset wedge 10, is a distinct novelty, and I wish to claim the same herein.

Preferably also I employ in the building of my improved shoe, the transverse arch

supporting structure, as explained in my said prior patent. Therefore in carrying out the preferred method, I assemble the upper materials and insole on the special form of last, 5 beat in the insole at the position illustrated substantially at 25. Then I supply therein the arch supporting member 30. This may be of any desired material, stiffness, flexibility or extent, such as felt, or other yielding, 10 able, compressible material, but preferably is to substantially fill the recess in the last, as for example, as seen in my said co-pending application, and is for the important purpose of supporting the inside 15 ball of the bottom of the foot, at the sesamoid bone and the first metatarsal phalangeal joint. This is one of the important features of my development in the improvement of corrective and correct shoe 20 structure giving to the shoe a transverse arch supporting effect directly at the shank portion of the ball of the foot, thus allowing more spring in the arch, more support to the shoe and giving greater freedom 25 of movement to the forepart and toes of the foot. This arch supporting feature, in combination with the accentuated fullness, preferably formed in the outside wall of the last and hence in the shoe, as well as the raised 30 sole structure and supporting feature on the inside, from the ball of the foot substantially to the rearmost portion of the heel, or at least to the lower part of the heel seat, where the oscalcis fits in, gives a greater 35 cupped heel seat than has heretofore been employed, as well as a firmer foot supporting wall structure, particularly on the inner arch of the foot, which latter feature is maintained by the wedge 10. The extra fullness 40 on the outer line is indicated at 33, Fig. 2, specially to accommodate the cuboid bone, thus providing perfect balance for the shoe, and preventing distortion from wear, and I believe that I am the first in this art of ortho- 45 pedic shoe construction, to combine the advantageous features of the fullness of the shoe at 33, the transverse arch supporting structure at the inside ball of the foot, and the providing of the arch support between 50 the insole and the outsole in the specially

formed and predetermined contour made in the last. All these features also in combination with the supporting wedge structure, give added novelty, but I consider the shoe construction with the supporting wedge as 55 fundamentally new.

My invention is further described and defined in the form of claims as follows:

1. The improved method of making boots and shoes, which consists in providing a last 60 with a disaligned portion at the heel breast to provide for raising the outsole at said disaligned position in the completed shoe, assembling upper and insole materials on a last, lasting the shoe, applying the outsole, beating the outsole in said disaligned portion at the inner shank part adjacent the heel breast from a normal horizontal position, applying a corrective wedge member from the heel breast portion rearwardly and centrally of the heel seat to offset said disaligned outsole, said wedge member being of greatest thickness at the heel breast and where exposed at the forward part of the heel, tapering rearwardly and centrally of the heel 70 seat, and thereupon applying the heel and finishing the shoe in the usual manner.

2. The improved process of making boots and shoes, which consists in first providing a last with a disaligned recess at one side 80 in the bottom portion at the rear of the ball of the shoe, said last having a lifted heel seat surface at said disaligned side and greater fullness in its outer curve, assembling shoe upper materials and an insole on said last, 85 beating the insole into the said recess, applying arch supporting material to the insole where beaten into the said last recess, securing the outsole, supplying a corrective wedge member from the heel breast portion 90 rearwardly and centrally of the heel seat, said corrective wedge member being substantially rectangular in form, and having its point of greatest thickness at the heel breast where the wedge is exposed, securing the 95 heel and finishing the shoe.

In testimony whereof, I have signed my name to this specification.

WILLIAM SAKLAD.
